CONTAINER WITH ROTARY CLOSURE

William Jacobs and Joseph S. Darling, New York, N. Y.

Application November 6, 1953, Serial No. 390,661

9 Claims. (Cl. 222—545)

This invention relates to an improved combination container and dispenser, and in particular relates to a dispenser having improved means for attachment thereof to the container.

This invention is an improvement over our previous U. S. patent application, Ser. No. 290,488, filed May 28, 1952, for Dispenser With Frictionally Interfitting Parts, now U. S. Patent No. 2,744,666.

In one embodiment, the container has an upstanding, cylindrical, preferably substantially rigid neck. The container may be a toothpaste tube or other squeezable tube, or may be a rigid container. The interior bore of the neck of the container is preferably substantially in the shape of an inverted frustro-cone.

The dispenser is preferably made of a relatively flexible plastic material, such as polyethylene, and includes a top portion which overlies the rim of the neck and which has a depending central boss which is preferably substantially in the shape of an inverted frustro-cone. The dispenser also includes a depending outer cylindrical flange surrounding the boss and spaced therefrom.

The depending boss of the dispenser is adapted to be frictionally inserted within the bore of the neck of the container, with said outer flange fitting frictionally round the outer face of said neck. Optionally and preferably, said neck and said outer wall have interfitting means to prevent accidental separation of the dispenser from the container.

The said boss of the dispenser is provided with a closure piece or valve similar to that shown in the aforementioned prior patent application. Accordingly, in one embodiment, the boss has a hollow, part-cylindrical opening whose axis extends transversely to the common axis of the dispenser and container, and which communicates through appropriate additional openings in the dispenser with the top and bottom faces of the dispenser. Said opening serves as a valve seat. The valve is substantially in the form of a solid cylinder and is adapted to be force-fitted through the top dispenser opening into said valve seat. The valve is turnable about the axis of said valve seat and is provided with a radially upwardly extending finger piece for such turning. The valve has at least one through-and-through diametrical opening which registers with both of said additional openings in one turned or dispensing position of the valve, and which is out of registration with at least one of said additional openings in another turned or closing position of the valve.

An important feature of the above construction is that the valve may be inserted in the central portion of the dispenser prior to assembling the dispenser with the container. The flexibility of the material of which the dispenser is made makes it easy to insert the valve therein. However, when the dispenser is mounted upon the container, the container neck rigidifies the structure and makes withdrawal of the valve difficult. Furthermore, the interfitting conical shapes of the neck bore and of

2

the boss make possible an excellent frictional interfit between these parts. The boss is compressed between the valve and the neck, thereby ensuring a tight fit of the valve in its seat.

It will be apparent that this improved dispenser is particularly suitable for use in dispensing pastes, as well as powder and liquids. The use of a screw cap is eliminated and the valve may be easily manipulated by the fingers of the user. Furthermore, the valve has clearly defined opening and closing positions, which eliminates the need for visual inspection to determine whether the dispenser is completely closed.

Other objects and advantages of this invention will become apparent from the following description, in conjunction with the annexed drawings, in which preferred embodiments are disclosed.

In the drawings:

Fig. 1 is a top plan view of the dispenser in accordance with our invention, and prior to mounting same upon a container.

Fig. 2 is a vertical cross-section through a combination container and dispenser in accordance with our invention, said container being shown partly broken away.

Fig. 3 is a vertical longitudinal section of said improved combination container and dispenser.

Fig. 4 is a view similar to Fig. 1, showing a modified dispenser.

Fig. 5 is a vertical cross section of the modified dispenser mounted upon a modified container, said container being partly broken away.

Fig. 6 is a vertical longitudinal section of the combination container and dispenser shown in Fig. 5.

Upon reference to the drawings in detail, and in particular to Figs. 1 to 3 thereof, it will be noted that they show a container 10 having an upstanding neck 11. Said container 10 may be of the collapsible type commonly used for dispensing paste or the like, or may optionally be rigid. For example, container 10 may be a tube for holding toothpaste.

Said neck 11 is preferably made of a substantially rigid material, but may optionally be made of a flexible and resilient material, such as polyethylene. Said neck 11 has a substantially cylindrical outer peripheral face 12 and an annular upper rim 13. Said outer peripheral face 12 optionally has a circumferentially extending groove 14 near the base thereof.

Neck 11 has a through-and-through axially extending bore 15 which is preferably of decreasing diameter from top to bottom. The peripheral wall of said bore 15 is preferably substantially in the shape of an inverted frustro-cone when container 10 is upright, as shown in the drawings.

Dispenser 16, which is adapted to be mounted on neck 11, is preferably molded in one piece from a material which is somewhat flexible and resilient, such as polyethylene.

Said dispenser 16 includes a top portion in the form of a disk 17 which is adapted to overlie rim 13 of neck 11. Said top portion 17 has a central depending boss or insert member 18 which is adapted to be interfitted within the bore 15 of neck 11, and an outer depending circumferential flange 19 which is adapted to be fitted over the outer peripheral face 12 of said neck 11.

Said boss 18 has an outer peripheral face 20 which is preferably downwardly tapered and which is preferably substantially in the shape of an inverted frustro-cone.

Said depending flange 19 is preferably substantially cylindrical in shape and preferably has an inwardly and circumferentially extending rib 21 on its inner face, near the bottom thereof. On the lower face of disk 17 of dis-

dispenser 16, boss 18 is spaced from flange 19 by an annulus 22.

Dispenser 16 has a top opening 23 which is located radially inwardly of annulus 27. Said opening 23 communicates at its bottom with a cavity 24 in dispenser 16, said cavity 24 extending downwardly into boss 18 to a point somewhat above the bottom face 25 thereof. Boss 18 has an axial bore 26 which extends upwardly from said lower face 25 and whose upper end communicates with cavity 24 at the bottom thereof.

Said cavity 24 is optionally in the shape of a part-cylinder, with its axis extending transversely to the axis of dispenser 16. In vertical cross-section, as shown in Fig. 2, the wall of cavity 24 is in the shape of a major arc of a circle, and is symmetrical with respect to the axis of dispenser 16.

The end faces of openings 23 are preferably coextensive with the end faces of cavity 24. Optionally and preferably, the side faces 27 of opening 23 slope downwardly and inwardly from the top of dispenser 16. Optionally, said side faces 27 are substantially planar.

Valve 28, which is adapted to be positioned within cavity 24, is preferably molded in one piece and is preferably somewhat more nearly rigid than dispenser 16. Optionally, valve 28 may be made of the same material as dispenser 16, the thickness of valve 28 imparting a substantial degree of rigidity thereto.

Valve 28 is preferably cylindrical in shape and has a through-and-through diametrically extending bore 29. Said valve 28 also has an outwardly radially extending finger piece 30, the axis of said finger piece 30 being offset in a counter-clockwise direction relative to the axis of bore 29, as taken in Fig. 2.

The manner of assembly of the above-described parts is as follows:

Valve 28 is first interfitted with dispenser 16. Valve 28 is positioned above dispenser 16 with the axis of valve 28 substantially parallel to the axis of cavity 24, with the peripheral face of said valve 28 resting upon the side faces 27 of opening 23 and with finger piece 30 uppermost. Said faces 27 act as cam surfaces. Valve 28 is pushed downwardly against said faces 27, and spreads said faces 27 apart until valve 28 passes through the bottom of opening 23 and into cavity 24, as shown in Figs. 2 and 3. The flexibility of dispenser 16 makes it easy to spread the faces 27 apart in order to insert valve 28 into cavity 24, and the resiliency of the material of dispenser 16 enables faces 27 to return to their normal positions after the insertion of valve 28.

In the inserted position of valve 28, its peripheral wall frictionally and slidably abuts the side wall of cavity 24 and the end faces of valve 28 frictionally and slidably abut the end faces of cavity 24, so that valve 28 is turnable about the axis of cavity 24. In said assembled position of valve 28, finger piece 30 extends upwardly through opening 23 and protrudes above the upper face of dispenser 16.

The respective side faces 27 of opening 23 serve as stops to the movement of finger piece 30 and hence of valve 28 in the respective clockwise and counter-clockwise directions. In the dispensing position of valve 28 shown in Fig. 2, in which finger base 30 abuts the left side face 27 of opening 23, the axis of bore 29 is aligned with the axis of bore 26, and said bores register with each other. Also, the upper end of bore 29 registers with opening 23. Accordingly, a through-and-through axial passage is provided through dispenser 16.

It will be apparent that when valve 28 is turned in a clockwise direction from its position of Fig. 2 to its closing position in which finger piece 30 abuts the other side face 27 of opening 23, the lower end of bore 29 is moved out of registration with bore 26. As a result, there is no through-and-through axial opening through dispenser 16. Preferably, also, in said closing position of valve 28, the

upper end of bore 29 is out of registration with opening 23.

After valve 28 is assembled with dispenser 16, dispenser 16 is assembled with container neck 11. Boss 18 is extended downwardly into bore 15, and flange 19 is extended around the outer face 12 of neck 11. Dispenser 16 is pushed downwardly to bring the outer peripheral face 20 of boss 18 into frictional interfit with the peripheral face of bore 15, the taper of said faces being substantially the same.

In the assembled position of dispenser 16 relative to container 10, annulus 22 preferably rests upon rim 13, with flange 19 frictionally abutting outer neck face 12, and with rib 21 positioned within groove 14. As a result, it is difficult for dispenser 16 to become accidentally separated from container 10, although dispenser 16 is optionally removable by snapping rib 21 out of groove 14 and moving dispenser 16 upwardly with respect to container 10. Optionally, boss 18 is slightly oversized in diameter relative to the bore 15 of neck 11, to insure the frictional engagement of the outer peripheral face 20 of boss 18 with the peripheral face of bore 15.

In said assembled position of dispenser 16 relative to container 10, the lower face 25 of boss 18 is optionally spaced above the lower face of dispenser 16, and the portion of bore 15 below said face 25 is optionally cylindrical.

In the fully assembled position of the parts, it is almost impossible to remove valve 28 from cavity 24, because the interposition of neck 11 between boss 18 and flange 19 substantially diminishes the extent of outward movement of side faces 27 of opening 23.

It will be apparent that with the parts fully assembled, the lower end of bore 26 communicates with the interior space of container 10. Therefore, in the dispensing position of valve 28, as shown in Fig. 2, it is possible to dispense the contents of container 10. When finger piece 30 abuts the other face 27, valve 28 effectively seals the contents of container 10 from removal therefrom.

It will be apparent that by proper dimensioning of the parts, it is possible to obtain a tighter fit between valve 28 and cavity 24, after insertion of boss 18 within neck 11, than is possible by the mere insertion of valve 28 within cavity 24. Accordingly, in the closed position of valve 28, an effective seal is provided, both between boss 18 and neck bore 15 and between valve 28 and cavity 24. Said seal is improved when boss 18 is optionally slightly oversized in diameter relative to bore 15.

As previously stated, dispenser 16 is preferably made from a material which is somewhat flexible and resilient. As a result, even if valve 28 is not perfectly seated within cavity 24 of dispenser 16 prior to the assembly of dispenser 16 with container 10, the forcible interfitting of the dispenser and the container results in a compression of boss 18 within neck bore 15, and hence results in a distortion of cavity 24 so as to cause a substantial conformity in shape between valve 28 and cavity 24.

Two possible modifications of the invention are shown in Figs. 4 to 6. In Figs. 4 to 6, parts corresponding to the parts of Figs. 1 to 3 are respectively designated by the same numbers with the addition of the reference letter "a."

As is shown in these views, neck 11a is provided on its outer peripheral face with a screw thread 9, and flange 19a of dispenser 16a is provided on its inner peripheral face with a cooperating screw thread 31. As a result, boss 18a may be inserted within the bore of neck 11a merely by screwing flange 19a on to said neck 11a.

As a further modification, valve 28a is substantially spherical in shape, and cavity 24a is substantially in the shape of a part sphere with the top thereof cut away. Top opening 23a is substantially in the shape of an inverted frusto-cone. The manner of assembly of valve 28a with dispenser 16a is entirely analogous to the manner of assembly of valve 28 with dispenser 16.

In the modified valve of Figs. 4 to 6, it is preferable to provide means for confining the axis of the valve bore

29a to movement in a vertical plane during turning movement of valve 28a, in order to insure proper registration of bore 29a with bore 26a in the dispensing position of valve 28a. Optionally, therefore, the peripheral face of valve 28a is provided with a groove 32 extending in a counter-clockwise direction from finger piece 30a toward the lower end of bore 29a, but terminating before reaching said bore 29a. Correspondingly, the face of cavity 24a is provided with an inwardly extending rib 33 located in a vertical plane and extending in a counter-clockwise direction from the top of said cavity 24a.

Rib 33 is substantially shorter than groove 32 and rides frictionally therein during turning movement of valve 28a. As a result of the provision of rib 33 and groove 32, valve 28a is only turnable about an axis which is transverse to the axis of dispenser 16a, so that bore 29a always registers with bore 26a in the dispensing position of finger piece 30a.

It will be apparent that the screw threads of Figs. 4 to 6 may be interchanged with the engaging means 14, 21 of Figs. 1 to 3.

While a preferred embodiment of this invention has been disclosed and various possible changes, omissions and advantages have been indicated, it will be apparent that various other changes, omissions and advantages may be made without departing from the scope and spirit of the invention.

What is claimed is:

1. A dispensing device comprising a container having a neck which has a through-and-through bore, a valve attachment made of flexible and resilient material and comprising a disk adapted to overlie the rim of said neck and having a central opening, a central boss depending from said disk and adapted to be inserted within said neck, said boss having an internal valve seat with a top opening communicating with said disk opening and a bottom opening communicating with the bottom of said boss, a valve frictionally and turnably seated within said valve seat, said valve having a through bore providing communication between said top opening and said bottom opening in one turned position of said valve and being out of said communication between said top opening and said bottom opening in another turned position thereof, a peripheral flange depending from said disk and adapted to be mounted upon the outer wall of said neck, and cooperating means carried by said outer wall of said neck and said peripheral flange for locking said flange upon said neck, said disk being adapted to be held frictionally against said rim and said boss being adapted to be held frictionally within said neck when said flange is locked upon said neck.

2. A dispensing device in accordance with claim 1, the outer peripheral face of said neck and the inner face of said flange being respectively cooperatively screw-threaded to serve as said means for locking said flange upon said neck.

3. A dispensing device in accordance with claim 1, said outer peripheral face of said neck having a circumferential groove and said flange having an inner circumferential rib which is adapted to fit within said groove, whereby said rim and said groove serve as said means for locking said flange upon said neck.

4. A dispensing device comprising a container having a neck which has a through-and-through bore which is generally of inverted frusto-conical shape, a valve attachment made of flexible and resilient material and comprising a disk adapted to overlie the rim of said neck and having a central opening, a central boss depending from said disk and having an outer peripheral surface which is generally of inverted frusto-conical shape and which is adapted to be inserted within said neck, said boss being normally slightly oversized in diameter relative to the bore of said neck, said boss having an internal valve seat

with a top opening communicating with said disk opening and a bottom opening communicating with the bottom of said boss, a valve seated within said valve seat and normally fitting somewhat loosely and turnably therein, said valve having a through bore providing communication between said top opening and said bottom opening in one turned position of said valve and being out of said communication between said top opening and said bottom opening in another turned position thereof, a peripheral flange depending from said disk and adapted to be mounted upon the outer wall of said neck, and cooperating means carried by said outer wall of said neck and said peripheral flange for locking said flange upon said neck, said disk being adapted to be thereby held frictionally and compressibly force-fitted within said neck, said valve being adapted to be thereby frictionally and turnably held within said valve seat as a result of the compression of said boss.

5. A dispensing device in accordance with claim 4, the outer peripheral face of said neck and the inner face of said flange being respectively cooperatively screw-threaded to serve as said means for locking said flange upon said neck.

6. A dispensing device in accordance with claim 4, said outer peripheral face of said neck having a circumferential groove and said flange having an inner circumferential rib which is adapted to fit within said groove, whereby said rim and said groove serve as said means for locking said flange upon said neck.

7. A dispensing device comprising a container having a neck which has a downwardly tapered, through-and-through bore, a valve attachment made of flexible and resilient material and comprising a disk adapted to overlie the rim of said neck and having a central opening, a central, downwardly tapered boss depending from said disk and adapted to be inserted within said neck, said boss being normally slightly oversized in diameter relative to said neck bore, said boss having an internal valve seat

35 with a top opening communicating with said disk opening and a bottom opening communicating with the bottom of said boss, a valve frictionally and turnably seated within said valve seat, said valve having a through bore providing communication between said top opening and said bottom opening in one turned position of said valve and being out of said communication between said top opening and said bottom opening in another turned position thereof, a peripheral flange depending from said disk and adapted to be mounted upon the outer wall of said neck, and cooperating means carried by said outer wall of said neck and said peripheral flange for locking said flange upon said neck, said disk being adapted to be held frictionally against said rim and said boss being adapted to be held frictionally within said neck when said flange is locked upon said neck.

40 8. A dispensing device in accordance with claim 7, the outer peripheral face of said neck and the inner face of said flange being respectively cooperatively screw-threaded to serve as said means for locking said flange upon said neck.

45 9. A dispensing device in accordance with claim 7, said outer peripheral face of said neck having a circumferential groove and said flange having an inner circumferential rib which is adapted to fit within said groove, whereby said rim and said groove serve as said means for locking said flange upon said neck.

50 10. A dispensing device in accordance with claim 7, said outer peripheral face of said neck having a circumferential groove and said flange having an inner circumferential rib which is adapted to fit within said groove, whereby said rim and said groove serve as said means for locking said flange upon said neck.

55 11. A dispensing device in accordance with claim 7, said outer peripheral face of said neck having a circumferential groove and said flange having an inner circumferential rib which is adapted to fit within said groove, whereby said rim and said groove serve as said means for locking said flange upon said neck.
